UNITED STATES PATENT OFFICE

THOMAS J. JUNKER, OF BUFFALO, NEW YORK

GAME

Application filed November 16, 1928. Serial No. 319,920.

This invention relates to a game having functionally and structurally new characteristics and by means of which an intriguing scheme of play is presented, the results of such play being dependent upon the skill of the person playing the game.

It is an object of the invention to furnish a device of this character in which, preferably, a missile is thrown, the accuracy of 10 missile-projection governing solely the results obtained.

A further object of the invention is that of constructing an apparatus of this nature in which a plurality of target portions are 15 preferably furnished and in which, moreover, different aggregations of hit targets will result in values obvious to the layman and of different importance.

An additional object is that of furnishing 20 a game, the several component parts of which will be individually rugged and simple in construction and capable of ready assemblage to provide a device which may be manufactured and sold at a relatively nominal 25 figure.

With these and further objects in mind reference is had to the attached sheets of drawings illustrating one practical embodiment of the invention and in which:—

30 Figure 1 is a partly fragmentary perspective view showing one unit of the game in set-up condition, certain of the parts being broken away to disclose underlying construction;

35 Fig. 2 is a similar but enlarged view of one of the game units, and

Fig. 3 is a diagrammatic representation of an audible signalling means which may be employed and forming part of the game.

40 According to the present invention it is proposed to employ a plurality of targets, each representing a certain value. To this end it is preferred that each target embody the representation of a card of a different 45 suit and/or value and the game is so constructed that the striking of a target will be visibly apparent and, if desirable, this result may also be registered audibly.

Thus, as in Figure 1, the numeral 5 indicates a cabinet constructed of any desirable

material and adjacent the rear end of which a series of supports 6 extend. A base portion 7 may form a part of the cabinet and, if desired, be inclined towards its forward outer end, at which point it may have a retaining groove 8 so that a missile 9 will 55 gravitate over this base towards the position occupied by the person playing the game.

Mounted upon the supports or bars 6 are a series of plaques 10 providing target members and the face of each of these elements conveniently bears the representation of a card face. Moreover, if desired, the supports may, at points directly underlying the corresponding targets, bear representations 60 indicative of such targets as, for example, 10 of clubs, king of spades, 8 of hearts, etc., it being preferred that targets of consecutive 65 value or of the same suit be not arranged adjacent to each other.

The mounting upon the bars or supports 70 is preferably achieved as, for example, by the structure shown in Fig. 2, in which it will be observed that the lower edge of each plaque is under-cut as at 11 and this lower edge 75 is hingedly attached as at 12 to the support. The parts may be so disposed that normally the plaques will incline slightly forwardly or else a resilient clip member 13 may be provided to maintain them in upright position. However, it will be obvious that when 80 struck any target will fall rearwardly to, for example, the position indicated in dotted lines.

Now with a view to providing means where- 85 by the struck targets will readily be visible, a number of desirable structures may be resorted to. Preferably, however, each of the supports carries, at a point adjacent its rear face, a source of illumination as, for exam- 90 ple a "neon" tube 14. Normally, none of the light rays emanating from such tube will strike against the face of any of the targets. However, when one of these targets is in- 95 clined rearwardly, the face thereof will be illuminated by the light rays and, particu- 100 larly, if these rays be colored, it will be apparent that the struck target will be dis- tinctively illuminated, so that the results achieved are outstanding. In order that the

position of the struck targets may be re-established, a series of rods 15 may be rockingly mounted by the cabinet or frame portions of the game and a shifting of these parts may occur as, for example, by providing cables 16 suitably available to the attendants of the game. In the embodiment illustrated the rods thus not alone serve the purpose of acting as stops for the struck targets but, moreover, when the cables 16 are pulled these rods re-establish the position of such targets. If desired, the rods may serve the further purpose of providing an audible signal in that, if each of the targets is grounded on one side of a circuit and these targets have conducting portions forming a part of them or their bodies are of conducting material, it will be apparent that, upon these bodies being inclined rearwardly to a position contacting with the rods, the circuit will be closed as for example, in Fig. 3, to operate an annunciator 17.

In this connection any number of desirable annunciator schemes well within the province of any skilled electrician will suggest themselves as being desirable for use in this association.

It will be obvious in playing a game of this nature that it will be an extremely difficult matter for a person to deliberately set-up a desired "hand". If a person be extremely skillful it is, of course, possible to strike targets representing, in aggregate, a royal straight flush. However, a man of ordinary skill, with a limited number of missiles, will, at best, be usually able to establish a pair. In this connection it will be observed that on each support 6 targets are preferably arranged so that not more than four of one suit appear. As a consequence the player cannot determine exactly the elevation necessary and strike targets which, in aggregate, give him a flush. Instead, he must deliberately pick out targets which he would endeavor to strike to achieve this result. Struck targets will, as aforesigned, be readily apparent and the operator may readily re-establish the position of the targets after the person has finished playing the game.

From the foregoing it will be understood that, among others, the objects specifically aforementioned are achieved. It will moreover be appreciated that numerous changes in structure and rearrangement of the parts might be resorted to readily without in the slightest departing from the spirit of the invention as defined by the claims.

Having described my invention, what I claim as new and desire to secure by Letters

60 Patent is:

1. A game including a plurality of movably mounted targets, a source of illumination, means normally directing the light rays from said source in a path clear of the face of said target and said target, when struck by a

missile, lying in a position in the path of said light rays.

2. A game including a plurality of rockingly mounted targets, each bearing upon its face the representation of a card, a source of illumination above and to the rear of the normal position of each of said targets and said targets assuming, when struck by a missile, a rearwardly inclined position within the path of the light rays from said source of illumination. 70 75

3. A game including a plurality of rockingly mounted targets, each bearing upon its face the representation of a card, a source of illumination above and to the rear of the normal position of each of said targets and said targets assuming, when struck by a missile, a rearwardly inclined position within the path of the light rays from said source of illumination, and target re-establishing means 80 85 positioned to the rear of the same and acting to limit the movement thereover.

4. A game including a plurality of rockingly mounted targets, each bearing upon its face the representation of a card, a source of illumination above and to the rear of the normal position of each of said targets and said targets assuming, when struck by a missile, a rearwardly inclined position within the path of the light rays from said source of illumination, target re-establishing means positioned to the rear of the same and acting to limit the movement thereover, a source of electrical energy connected to said last-named means and targets and registering means 90 95 within the circuit thus provided and being actuated upon a target being rocked rearwardly. 100

In testimony whereof I affix my signature.

THOMAS J. JUNKER.
